CLAIM

The ornamental design for a planter row frame support, as shown and described.

DESCRIPTION

FIG. 1 is a side elevational view of a planter row frame support showing our new design, the planter row unit shown in broken lines is for illustrative purposes only; FIG. 2 is an enlarged top, rear, and side perspective view thereof;

FIG. 3 is an enlarged bottom, rear and side perspective view thereof;

FIG. 4 is an enlarged bottom, front and opposite side perspective view thereof.

The inner surfaces are unornamented and generally follow the outer contours.
